UNITED STATES PATENT OFFICE.

FRANK M. PIERCE, OF CHICAGO, ILLINOIS, ASSIGNOR TO PIERCE WRAPPING MACHINE COMPANY, OF CHICAGO, ILLINOIS, A CORPORATION OF ILLINOIS.

SHUTTLE FOLDING AND GUIDING DEVICE.

1,196,022.

Specification of Letters Patent. Patented Aug. 29, 1916.

Application filed January 2, 1915. Serial No. 101.

To all whom it may concern:

Be it known that I, FRANK M. PIERCE, a citizen of the United States, and a resident of the city of Chicago, in the county of Cook and State of Illinois, have invented certain new and useful Improvements in Shuttle Folding and Guiding Devices; and I do hereby declare that the following is a full, clear, and exact description of the same, reference being had to the accompanying drawings, and to the numerals of reference marked thereon, which form a part of this specification.

This invention relates to an improved folding and guiding device for paper carried upon a rotatable shuttle such as used in tire wrapping machines wherein the tire or other article to be wrapped is placed in the machine and rotated while a shuttle carrying a reel of paper is rotated rapidly through the eye thereof, applying a wrapper helically thereto.

Heretofore the strip of paper taken from the reel carried upon the shuttle has been led through a folder plate and then around suitable guiding means such as a roller, which serves to crease the fold in the paper coming from the folder plate and guides the strip to the article being wrapped. In the present invention however a unitary device is provided for folding, creasing and guiding the paper to the article to be wrapped, and the device is furthermore adjustably mounted upon the shuttle so that the angle thereof may be changed according to the position of the article in the machine, inasmuch as articles of different size are sometimes placed in relatively different positions in the machine when being wrapped.

It is an object therefore of this invention to construct a device attachable to a shuttle adapted to receive a strip of paper running therethrough acting to curl the paper over to form a fold and the paper then being drawn around a suitable extension on the device serving to crease said fold, and suitably guide the creased folded paper to the article being wrapped.

It is also an important object of this invention to construct a unitary folding, creasing and guiding device which is adjustably mounted upon a shuttle carrying a reel of paper for application to an article to be wrapped.

It is finally an object of this invention to construct a device simple in operation and construction, greatly improving the wrapping operation of the machine to which it is attached.

The invention (in a preferred form) is illustrated in the drawings, and is more fully pointed out and defined in the appended claims.

In the drawings: Figure 1 is a front face view of a shuttle equipped with a device embodying the principles of my invention. Fig. 2 is an enlarged outer face view of the device. Fig. 3 is a detail section taken on line 3-3 of Fig. 2. Fig. 4 is an interior face view of the device detached from the shuttle.

As shown in the drawings, a shuttle is illustrated in Fig. 1, and consists of a main section 1, and a supplementary section 2, which is hinged thereto upon a stud bolt 3, and held locked in closed position by locking mechanism denoted as a whole by the reference numeral 4, at the junction of said hingedly connected shuttle sections. Secured on the side face of the main shuttle section 1, is a stud bolt 5, on which a paper carrying reel 6, is journaled, and on which is disposed a reel of paper 7. A tension device for the paper led from the paper reel 6, is provided, comprising a plate 8, secured to the surface of said main shuttle section 1, and provided with a group of rounded pins 9, 10 and 11, respectively, around which the paper is trained. From the tension mechanism the strip of paper is led to a folding, creasing and guiding device which consists of a sheet of metal 12, which is bent upwardly from its lower edge, affording an upright plate, as indicated by the reference numeral 13, and which, as clearly shown in Fig. 4, in dotted lines, tapers downwardly along its upper edge to a vertical cutaway edge 14, and then tapers downwardly again therefrom at an angle of about thirty degrees, although the particular angle is immaterial, to the bottom edge of the plate.

The upper margin of the sheet of metal 12, is folded over and flared outwardly rearwardly of the device; that is, toward the entrance end thereof, as denoted by the reference numeral 15, and increases in width, as clearly shown in Fig. 4, from the entrance end of the device toward the exit end there-

of, and is therefore equal in depth to the width of the main plate 12. Integral with said folded extension 15, at the forward or wide end thereof, is a curved extension 16, which, 5 as clearly shown in plan view in Fig. 1, is angled out of the plane thereof. The folder plate is secured upon a plate 17, which may be attached to the rear surface of the main plate 12, of the folder, in any suitable manner, said plate 17, having formed at one end a cylindrical member 18, through which a bolt 19, extends. The lower end 20, of said bolt 19, is bent at an angle thereto to engage 10 perpendicularly through an aperture in the wall of the shuttle section 1, and on said lower end 20, is a nut 21, which may be loosened to permit adjustment of said bolt. It is apparent, therefore, by reference to Fig. 3, that the bolt 19, is always at an angle 15 with respect to the surface of the wall of the shuttle section, and an angled washer 22, is engaged upon said angled bolt between the cylindrical member 18, and the surface of the shuttle section. The opposite surfaces 20 of said washer are not parallel but at an angle formed to correspond with the angularity of the bolt 19. It is therefore apparent that the folder device may be adjusted 25 about the pivot bolt 19, into various positions, all of which are angled with respect to the surface of the wall of the shuttle, and may be retained in any adjusted position merely by tightening the nut 21.

The operation is as follows: The paper is 30 led from the paper reel and thence through the tension mechanism, and enters the folder plate at the end adjacent the cylindrical member 18, the lower edge of the paper strip tracking upon that portion of the 35 metal connecting the plates 12 and 13, along the lower edge of the device. The upper edge contacts the flared, curved portion 15, and is thereby folded over and downwardly around the upper margin of the plate 13. 40 Thus a fold is created in the paper, and as the same is drawn from the folder device around the curved member 16, thereof, said fold is creased and the creased paper is applied to the article. Inasmuch as the folder 45 device is mounted upon the bolt 19, which is always angled with respect to the surface of the shuttle section 1, it is apparent that the proper tilt to the folding device is secured in all positions of adjustment, and the folder 50 device may be readily adjusted by loosening the nut 21, and swinging said folder device into various positions.

I am aware that various details of construction and operation may be varied without departing from the principles of this 55 invention. I therefore do not purpose limit-

ing the patent granted, otherwise than necessitated by the prior art.

I claim as my invention:

1. In a device of the class described a 65 plate bent to afford a portion parallel thereto with the edge tapered off and another portion bent thereover and flared therefrom and tapered downwardly substantially uniformly with the taper of said other portion 70 and terminating in a curved portion.

2. A device of the class described embracing a plate, one margin of which is bent thereover and flared outwardly along the upper edge, another portion of which is bent 75 upwardly from the lower edge beneath said first mentioned portion, and a curved portion formed integral with the end of said first mentioned bent portion.

3. In a device of the class described the 80 combination with a shuttle, of a folder plate member pivotally mounted thereon at an angle thereto.

4. In a device of the class described the combination with a shuttle, of stationary 85 folding and creasing mechanisms adjustably mounted on the shuttle at an angle thereto.

5. In a device of the class described the combination with a shuttle, of unitary folding, guiding and creasing means adjustably 90 secured at an angle thereto.

6. In a device of the class described a folder plate adapted to receive paper drawn therethrough to fold the same, and a curved extension on said plate to crease the fold in 95 the paper as it is drawn thereover.

7. The combination with a shuttle, of a pivotally mounted folder plate thereon, the pivotal axis thereof inclined in two different directions with respect to the shuttle. 100

8. In a folder device for a wrapping machine shuttle, a pintle bolt mounted in an inclined position on the shuttle, a plate pivotally mounted thereon, and a guide plate integral therewith adapted to fold the wrap- 105 ping material.

9. In a device of the class described, a pintle bolt mounted in an inclined position, a plate pivotally mounted thereon, a guide plate integral therewith tapered to afford a 110 narrow restricted nozzle, and having one edge turned over said plate to fold wrapping material thereover as it is drawn through said guide plate.

In testimony whereof I have hereunto 115 subscribed my name in the presence of two subscribing witnesses.

FRANK M. PIERCE.
